UNITED STATES PATENT OFFICE.

GEORGE M. KENT, OF MANCHESTER, NEW HAMPSHIRE.

DESIGN FOR A VEHICLE SIGNAL.

Application filed October 25, 1921. Serial No. 510,859. Term of patent 7 years.

To all whom it may concern:

Be it known that I, GEORGE M. KENT, a citizen of the United States, residing at Manchester, in the county of Hillsborough and State of New Hampshire, have invented a new, original, and ornamental Design for a Vehicle Signal, of which the following is a specification.

The figure is a front view in elevation of a vehicle signal, showing my new design.

I claim:

The ornamental design for a vehicle signal, as shown.

In testimony whereof I hereunto affix my signature.

GEORGE M. KENT.
